RECLOSABLE CARTON

Marion F. Moore, Downers Grove, Ill., assignor to Container Corporation of America, Chicago, Ill., a corporation of Delaware

Filed June 17, 1957, Ser. No. 665,944

1 Claim. (Cl. 229—87)

The present invention relates to reclosable cartons of the type particularly adapted for the packaging of small articles of clothing, or food products, such as strips or slices of meats or cheese.

Among the important objects of the invention are to provide an efficient and economical one-piece paperboard carton with a window opening which utilizes the stock cut from such opening as a functional portion of the carton, in combination with other parts, whereby the carton is adapted to enclose the contents completely and thereby obviate the need for overwrapping.

Another object is to provide a carton formed from a minimum amount of paperboard and to construct the carton so as to be reclosed easily after a portion of the contents has been removed.

Another object of the invention is to provide a carton having a window opening formed by cutting a hinged panel therefrom and closing the window with a transparent sheet secured around three sides of the window panel on its inside surface, such sheet being extended to overlie the portion of the carton beyond the fourth side of the window opening to completely close the opening from the inside.

Other objects and advantages of the present invention will become apparent as the description proceeds.

In the drawings:

Fig. 1 is a perspective view of one form of the carton as it appears in closed condition;

Fig. 2 is a plan view of the carton as it appears when ready to receive its contents;

Fig. 3 is a perspective view of the carton with one of the side flaps turned in to the position where it would cover an edge portion of the contents and with the carton back wall ready to be swung down to closed position;

Fig. 4 is a perspective view of a modified form of carton utilizing a similar arrangement of back wall which is cut from the central part of the front wall to form a window opening, this form of carton having edge walls of substantial depth;

Fig. 5 is a plan view of the carton shown in Fig. 4 with the back wall in place within the window opening;

Fig. 6 is a perspective view of the carton with side walls secured in upright position, with side wall flaps in a position to overlie the carton contents, and with the back wall ready to be swung down to overlie the side flaps; and

Fig. 7 is a fragmentary sectional view taken along line 7—7 of Fig. 4 looking in the direction of the arrows.

The carton of the present invention finds advantageous use for articles such as women's hosiery, gloves, handkerchiefs and other small cloth articles, food products, such as sliced meat and other sliced food, and is particularly convenient to package a group of items of which it is desired to remove only one or, at most, only a few at a time then reclose the carton. The construction of the carton is such that it completely encloses its contents and makes overwrapping unnecessary. In its preferred form the carton comprises essentially a main panel serv-

ing as the carton front wall from which a window opening is cut and the panel obtained from the opening is cut only on three sides to form a hinged back wall. The front wall has hinged marginal flaps to close three marginal edges and to cooperate with the back wall to close the carton completely.

In the modified form of the invention, instead of hinging the back wall and marginal flaps directly on the main panel, they are connected to the main panel by narrow portions forming side and end walls for the carton. This modified form, having more depth, is advantageous for commodities such as paper napkins and other paper products, school supplies, candies, bakery products, such as small pies, and many other products which it is desirable to package so that the contents may be viewed readily.

Referring first to Figs. 1, 2 and 3, the carton indicated as a whole at 10 is preferably of the "no depth" type and is formed from a single blank of foldable paperboard cut and creased or scored to provide a main panel or front wall 11, and excised panel 12 comprising a back wall cut from within the contour of the front wall on three sides only and joined to the front wall along fold line 13. The opening 14 from which the panel 12 is cut provides a window which is preferably closed by gluing a transparent panel 15 thereover, preferably on the surface which is to form the inside of the carton.

The strips around the window opening are left sufficiently wide to give adequate rigidity to the front wall 30 panel 11. The two side strips carry hinged thereto side edge closure flaps 16, 16 defined from the side strips by fold lines 17, 17. The portion opposite the hinge of the back wall, and for convenience termed the "bottom strip," has hinged thereon a bottom edge closure flap 18, defined from the bottom strip by a fold line 19. The bottom edge closure flap preferably extends along the entire length of the main or top panel 11, but the side closure flaps 16, 16 are cut so that their ends adjacent the hinge connection 13 between the top panel 11 and bottom panel 12 will not extend beyond such hinge line, if extended.

The transparent panel 15 preferably extends across the opening 14 on three of its sides approximately to the fold lines 17, 17 and 19 and preferably somewhat beyond the hinge line 13 between the front wall panel and excised panel 12, and may be secured along the inside edge of panel 12 adjacent hinge line 13. By first folding inward the flaps 16, 16, then the back wall panel 12 and, finally, the flap 18, the contents of the carton may be closed completely.

For the purpose of securing the carton in closed condition the panel 12 may be formed with a pair of spaced slits 21, 21 into which are received lock tongues 22, 22 formed on the outer edge of the bottom edge closure flap 18.

It is to be noted that by cutting away the ends of flaps 16, 16 adjacent the hinge line 13, the ends of these flaps will lie inside the fold between panels 11 and 12. By folding over panel 12, with consequent folding of the narrow portion 15a of the transparent panel, after the contents have been placed on such transparent panel and then folding the side flaps inward, the carton corner portions at the ends of the fold line 13 will be closed.

In the modified form of the invention, illustrated in Figs. 4 to 7 inclusive, the carton, indicated as a whole at 25, is formed from a blank of folding paperboard cut and creased or scored to provide a main panel or top wall 26, a bottom wall panel 27 cut from within the contour of the main panel on three sides only and joined to the main or top panel by an intermediate narrow panel 28 defined from the panel 27 by fold line 29 and from the panel 26 by fold line 30. The two panels 27 and 28 are

for convenience referred to as the excised panel. The opening 31 from which the excised panel is cut provides a window opening which is closed by gluing a transparent panel 32 thereover on the surface which is to form the inside of the carton. The preferred manner of gluing the transparent panel on to panel 26 is first to fold back the excised panel until it lies substantially in the plane of the remainder of the carton and then attach the transparent panel around the three sides of the window opening with a narrow marginal edge portion 32a extending beyond the hinge line of the excised panel.

The top wall panel 26 has extending therefrom end walls 34 and 35 and side walls 36 and 37. The wall 35 is defined from the top wall panel by fold line 38. The side walls 36 and 37 are defined from the top panel by fold lines 39 and 40 and the end wall 34 is hinged to the top panel along two short fold lines 41 and 42 aligned with hinge line 29 which joins the end wall 34 and narrow panel 28.

Corner flaps 44, 44 and 45, 45 are provided on the respective end walls 34 and 35 and may be secured to the adjacent ends of the side walls 36, 37 by adhesive, as indicated, or in any other customary manner.

The narrow panel 28 is preferably secured to the interior surface of the end wall 34 by applying adhesive between these parts. This may be done before the carton leaves the box factory or can be done at the packer's plant. In any event the blanks may be transported in flat form.

An additional closure flap 46 is provided, hinged on the outer edge of wall 35 and at its outer edge the flap 46 is formed with a locking tongue 47 adapted to enter a slit 48 formed in the panel 27. Side flaps 49 and 50 are hinged to the respective walls 36 and 37, adapted to be turned in to form a part of the bottom closure.

The carton is preferably loaded by placing the top wall panel 26 on a supporting surface with the bottom panel 27, flaps 49 and 50 and flap 46 either extending upwardly or folded outwardly. After the carton is filled the side flaps 49 and 50 will first be turned in, the panel 27 will then be swung down to overlie the flaps 49 and 50 and finally the flap 46 will be folded over and the tongue 47 engaged within the slit 48 in panel 27. The package will then be complete and ready for shipment.

It is apparent that the present invention provides a simple and easily usable carton which can be readily formed in the box plant, shipped flat to the packer and by the packer quickly set up, filled and closed. Due to the construction and arrangement of the transparent panel and the overlapping closure flaps the carton will completely enclose the contents. The contents may be easily removed by the user and, if only a part of the contents is removed, the carton can be closed with facility. The amount of overlap of the parts of the carton is relatively small whereby a high degree of economy of construction is realized.

While the foregoing description set forth preferred embodiments of the invention, various changes in the con-

struction may be made without departing from the spirit of the invention, and it is therefore desired that the present embodiments be considered in all respects as illustrative and not restrictive, reference being had to the appended claim rather than to the foregoing description to indicate the scope of the invention.

I claim:

A reclosable, no-depth carton formed from a single blank of foldable paperboard cut and creased to provide a rectangular front wall panel, a rectangular back wall panel cut from the front wall panel along three sides to form a window opening, the back wall panel having its attached edge hingedly connected to the front wall panel along a fold line spaced from and generally parallel to one edge of the front wall, the outer free edge of the back wall panel being spaced from the other edge of the front wall, the material between such back wall free edge and the adjacent outer edge of the front wall panel constituting a "bottom strip" for the carton, a bottom edge closure flap hinged to the outer edge of the bottom strip, a side edge closure flap hinged at each of the sides of the front wall panel and each having a length in a direction normal to its hinge line such that, when infolded, a portion of its edge will be in overlapping relation to a side edge of the back wall panel, and each side edge closure flap having an extent parallel to its hinge line comparable to but not greater than the space between the back wall panel hinge line, if extended, and the bottom edge closure flap hinge line, whereby, when the side flaps are folded against the front wall panel, the back wall panel and bottom edge closure flap may thereafter be folded to lie against a portion of the outer surfaces of the side closure flaps, the bottom edge closure flap being of an extent sufficient to overlap a portion of the outer free edge of the back wall panel, means for releasably securing the back wall panel and bottom edge closure flap together, and a transparent, flexible sheet secured to the front panel over the window opening on the surface of the front panel which the back panel faces when in closed position, such transparent sheet having an extended edge portion folded to lie against the adjoining portion of the transparent sheet when the carton is closed and such edge portion being secured to the inside surface of the back wall panel along its hinge connection with the front wall panel.
